UNITED STATES PATENT OFFICE.

HARVEY SEWARD, OF PETERSBURG, VIRGINIA, ASSIGNOR TO SEWARD TRUNK AND BAG COMPANY, OF PETERSBURG, VIRGINIA, A CORPORATION OF VIRGINIA.

WARDROBE-TRUNK.

1,135,404.

Specification of Letters Patent. Patented Apr. 13, 1915.

Application filed December 29, 1914. Serial No. 879,500.

To all whom it may concern:

Be it known that I, HARVEY SEWARD, a citizen of the United States, residing at Petersburg, in the county of Dinwiddie and State of Virginia, have invented certain new and useful Improvements in Wardrobe-Trunks, of which the following is a specification, reference being had therein to the accompanying drawing.

10 This invention relates to certain new and useful improvements in wardrobe trunks and more particularly to a gate hanger especially adapted to be used in connection with this class of trunk for supporting the 15 garment hangers in the hanging compartment thereof; the object being to provide a novel form of gate hanger having brackets carried thereby forming a two-point suspension for the garment hangers so as to prevent the same from swinging when the garments are arranged thereon when the trunk is being shipped.

Another object of the invention is to provide a gate hanger which is so mounted that 25 the same can be swung outwardly from its compartment in order to allow the garments supported thereby, to be accessible so that they can be readily placed in position or removed therefrom; means being provided for 30 locking the gate hanger in closed position so as to hold the garments within the hanging compartment.

Another object of the invention is to provide a gate hanger which is exceedingly 35 simple and cheap in construction and one which is preferably formed of a single piece of metal having spaced brackets projecting laterally therefrom upon which the garment hangers are spaced and supported in such a 40 manner that they are firmly held in position.

Another object of the invention is to provide a trunk with a body portion having a cover portion substantially the same size forming a hanging compartment in which 45 the gate hanger is mounted.

Other and further objects and advantages of the invention will be hereinafter set forth and the novel features thereof defined by the appended claims.

50 In the drawings—Figure 1, is a front elevation of a portion of my improved construction of wardrobe trunk showing the gate hanger in closed position with the

hanging compartment; Fig. 2, is a horizontal section through the trunk showing the 55 gate hanger in dotted lines, swung outwardly; Fig. 3, is a vertical section through the gate hanger showing one of the bracket arms; Fig. 4, is a perspective of the hanger and its supporting means; Fig. 5, is a detail 60 horizontal section through the catch showing the latch for the hanger in plan view; and Fig. 6, is a detail perspective of the latch.

Like numerals of reference refer to like 65 parts in the several figures of the drawings.

In the drawings, 1 indicates the body portion of my improved construction of wardrobe trunk, 2 the cover therefor which is connected thereto by hinges 3 in the ordinary manner; said cover having a hanging compartment 4 at one end and in the form of trunk herein shown, one end of the body portion and the cover portion is provided with swelled portions so as to prevent the 75 trunk from being placed upon this end; these swelled portions forming the top of the wardrobe formed thereby.

Secured to the inner wall of the cover portion within the hanging compartment, is a 80 plate 5 which is secured therein by rivets 6; said plate having a vertically disposed eye 7 in which is mounted a pintle 8 over the ends of which are arranged the eyes 9 of a gate hanger 10 herein shown formed of a 85 single piece of metal forming parallel bars connected together at one end by a vertical bar 11. By this manner of forming the gate hanger, the same is mounted upon the pintle 8 in such a manner that the same is free to 90 swing outwardly for the purpose herein-after fully described.

In order to provide means for locking the hanger 10 in closed position within the compartment, I provide the wall of the compartment with a catch 12 formed of a single piece of metal having parallel slits at one end, the intermediate tongue formed thereby being bent to form a catch proper 13 which is adapted to be engaged by a pivoted latch 14 100 mounted in a housing 15 secured to the vertical bar 11 of the gate hanger, as clearly shown; a suitable flat spring 16 being arranged within the housing under the pivoted latch having one end connected thereto so as 105 to hold the same in position to engage the

catch 13 allowing the latch to yield when the same is moved into engagement with the catch.

The form of latch herein shown, comprises 5 a single piece of metal bent to form a catch proper at one end having laterally projecting lugs forming pivots; the opposite end of the same being extended from the housing 15 to form a handle by the depression of 10 which, the latch is thrown out of the path of the catch 13 so as to release the gate hanger so that the same can be swung outwardly.

Connected to the swinging gate are spaced 15 brackets 17 and 18 preferably formed of a single piece of wire bent to the shape shown and secured to the gate by rivets or any other suitable fastening means; said brackets having upwardly projecting ends 17' and 20 18' so as to prevent the garment hangers 19 from sliding off of the ends thereof and it will be seen that in connection with these brackets I employ a peculiar shape of garment hanger so as to provide a two-point suspension 25 therefor so as to prevent the hangers from rocking upon their supports when the trunk is being shipped. These brackets 17 and 18 project laterally into the clothes compartment in such a manner that the garment hangers carried thereby are moved into 30 the compartment when the gate is swung into closed position and out of the compartment when the gate is swung outwardly and by swinging the gate outwardly at right angles 35 to its closed position, the garment hangers 19 can be placed in position upon the brackets 17 and 18 or removed therefrom.

The garment hangers 19 as herein shown, are preferably formed of wood having coat- 40 receiving portions adjacent their lower ends and hooks at their upper ends which straddle the brackets 17 and 18 in such a manner that the same are free to slide upon the brackets but are prevented from swinging 45 out of a horizontal plane.

I claim:

1. In a wardrobe trunk, the combination 45 with a body portion and a cover portion pivotally connected together, said cover portion 50 having a hanging compartment, of a gate hanger pivotally mounted within the cover portion, brackets extending laterally from

said gate hanger, and garment hangers having a two-point suspension mounted upon said brackets.

2. In a wardrobe trunk, the combination with a hanging compartment, of a plate secured within said compartment to one side thereof, said plate having a vertically disposed eye, a gate hanger formed of a single piece of metal having parallel bars terminating in eyes adapted to register with the eye of said plate, a pintle extending through said eyes, means for fastening said gate hanger in closed position within said compartment, and laterally projecting spaced brackets carried by said hanger having upwardly projecting end portions.

3. A wardrobe trunk, comprising a body portion and a cover portion pivotally connected together, a gate hanger pivotally mounted within the cover portion and capable of swinging outwardly and away from the body portion, said gate hanger having spaced laterally projecting brackets 75 connected thereto.

4. A wardrobe trunk, comprising a body portion and a cover portion pivotally connected together, a gate hanger pivotally mounted within the cover portion on the 80 side opposite to its connection with the body portion, said gate hanger being capable of swinging outwardly at right angles to the cover portion, and brackets carried by said hanger having upwardly projecting end portions.

5. A wardrobe trunk, comprising a body portion and a cover portion pivotally connected together, said cover portion having a hanging compartment, a swinging frame 90 pivotally connected to the free side of said cover portion within said hanging compartment, and brackets formed of single pieces of wire connected to the parallel bars of said frame having laterally projecting portions 95 terminating in upwardly projecting portions forming two-point suspension means for garment hangers.

In testimony whereof I hereunto affix my signature in the presence of two witnesses.

HARVEY SEWARD.
